UNITED STATES PATENT OFFICE.

LOUIS ALAN HAZELTINE, OF HOBOKEN, NEW JERSEY, ASSIGNOR TO HAZELTINE CORPORATION, A CORPORATION OF DELAWARE.

WAVE SIGNALING SYSTEM.

Original application filed February 27, 1925, Serial No. 12,000, and in Canada May 4, 1925. Divided and this application filed September 24, 1927. Serial No. 221,647.

This invention relates to wave signaling systems, particularly radio receiving systems, and has for its general object the provision of a radio receiver which is highly 5 sensitive and highly selective and at the same time is simple to control. This result is attained primarily by employing tuned radio-frequency amplification, preferably in more than one stage of a vacuum-tube amplifier, with the complete elimination of coupling between the plate circuits and the grid circuits, except through the mutual conductance of the amplifying tubes, and with an arrangement of the amplifier trans- 10 formers so that their input conductances are related in a certain way to the conductances of the vacuum tubes. The manner in which the conductances are related and the advantages thereof are more fully explained in 15 my co-pending U. S. application entitled "Wave signaling systems." Serial No. 12,000, filed February 27, 1925, of which the present application is a division.

The elimination of coupling between the 20 plate circuits and grid circuits of the vacuum tubes is accomplished by the cooperation of three steps: First, the arrangement of the amplifier transformers so that there is substantially no magnetic coupling be- 25 tween any two of them; second, the avoidance in the wiring of any substantial impedance common to two or more tuned cir- 30 cuits; and third, the neutralization of natural capacity coupling inherent between the 35 tuned circuits including, particularly, that due to the capacity between the grid and plate of the vacuum tube.

The elimination of undesirable coupling 40 between the plate and grid circuits results in the prevention of feed-back or regenerative action, and consequently there is no tendency towards the production of local os- 45 cillations. The neutralization of such undesired capacity coupling is in general ex- plained in my U. S. Patents Nos. 1,489,228 and 1,533,858.

The particular object of the present in- 50 vention is the provision of suitable and readily available means for the reduction of the undesirable effects of capacity coupling between circuits of one or more of the vacuum tubes, which may or may not be connected adjacently, by arranging apparatus in an input circuit and apparatus in a

succeeding input circuit or output circuit 55 so as to have natural capacity therebetween, and adjusting the natural capacity to attain at least partial neutralization of such undesired capacity coupling. To produce satisfactory results by itself, this partial neutralization should at least be sufficient to prevent 60 undesired oscillations due to the capacity coupling. In order to effect such neutralization, it is necessary that the polarity of certain points in the input and output cir- 65 cuits bear the proper relation to each other, as will hereinafter be explained in connec- tion with the drawings.

Referring to the drawings: 70 Figures 1^a and 1^b show a plan and an elevation, respectively, of a tuned radio-frequency amplifier to which this invention has been advantageously applied.

Figure 1^c shows the diagram of connec- 75 tions of the receiver of Figures 1^a and 1^b.

Figure 1^d shows the structure of the radio- 80 frequency amplifier transformers of Figures 1^a and 1^b.

Figure 1^e shows a modification of the cir- 85 cuit of Figure 1^c.

Figure 2 shows the connections of a radio receiver embodying this invention and em- 90 ploying natural inherent capacity for the neutralization of the capacity coupling ef- fectively existing between the input and 95 output circuits of a vacuum tube, with cer- tain novel means for adjusting the neutralizing capacity.

In the radio receiver represented in Fig- 100 ures 1^a and 1^b there are three radio-fre- quency transformers T_a, T₁, T₂, each asso- ciated with a tuning condenser C_a, C₁, C₂. Each coil is mounted on the back of its condenser for the purpose of keeping as short as possible the leads between them 105 and for other purpose, as disclosed in my U. S. Letters Patent No. 1,577,421 and in my co-pending application Serial No. 40,488, filed June 30, 1925. The vacuum tubes are mounted adjacent to the coils and condensers with which they are associated, also in order to keep the connecting leads as short as possible. The coils of each trans- 110 former are preferably of the single-layer type, as illustrated in Figure 1^d, and are mounted with axes parallel and at an angle of substantially 55 degrees with the line of centers, this being a convenient arrangement 115

resulting in zero magnetic coupling between any two of the transformers, as described in my patent and co-pending application just referred to. Care is also taken to avoid 5 magnetic coupling between stages that might be due to closed conducting loops linked with the fields of two or more transformers. Such loops might exist in a supporting metal framework, or in the leads from the batteries 10 which leads are therefore preferably bunched together.

Figure 1^e shows the diagram of connections for the receiver of Figures 1^a and 1^b. The reflex principle is employed by which 15 radio-frequency amplifying tubes A₁ and A₂ serve also as audio-frequency amplifying tubes through the use of two audio-frequency transformers T_{a1} and T_{a2}. The jacks J_D, J₁, J₂ enable a head telephone receiver, or 20 loud speaker, to be plugged in the plate circuit of the detector tube or either of the audio-frequency amplifier tubes.

Since each coil of an audio-frequency transformer has a high impedance to radio-frequency current, by-pass condensers C_{g1}, C_{g2}, C_{p1}, C_{p2}, C_{pd} are arranged to provide low- 25 impedance return paths for the radio-frequency grid and plate currents direct to the respective filaments. This keeps radio-frequency currents out of the common battery 30 leads, which may have sufficient reactive impedance as to cause objectionable coupling if they carry radio-frequency currents of different stages. The grid by-pass capacities 35 C_{g1}, C_{g2} may be of the order of one ten-thousandths microfarad, and the plate by-pass capacities C_{p1}, C_{p2}, C_{pd} may be of the order of one one-thousandths microfarad, these 40 values giving low radio-frequency impedances, but sufficiently high audio-frequency 45 impedances not to shunt unduly the audio-frequency transformer coils and so lower the audio-frequency amplification. The leads to the by-pass condensers should be short to minimize their reactive impedances.

In case the radio-frequency current in the plate circuit of detector tube D passes in appreciable amount through the primary of T_{a1} and so couples tube D with tube A₁, 50 then a radio-frequency impedance L_{pd} (Figure 1^e) may be inserted in the lead from the plate of tube D, and a condenser C'_{pd} may be connected directly from this plate to the filament. Care must be taken that the 55 impedance coil L_{pd} is not coupled magnetically to any of the radio-frequency transformers.

The filament system should be grounded, 60 preferably at X, Figure 1^e, so that radio-frequency current passing from the antenna through the natural capacity between the coils of T_a will flow directly to ground, and not through the battery leads to the other tuned circuits and thence through their natural capacities to ground, which would result 65 in undesirable coupling between the stages.

Coupling between the plate circuit and the grid circuit of tube A₁, due to the natural capacity C_{ei} between the grid with its connected apparatus and the plate with its connected apparatus, is neutralized by the neutralizing capacity C_{n1} connected between the grid and the auxiliary coil ab, which in Figure 1^e is a portion of the secondary coil ac of the transformer T₁. As explained in my U. S. Letters Patent No. 1,489,228, neutralization will be effected when the primary coil de and the auxiliary coil ab are closely coupled electromagnetically and have terminals a and e, which connect to the filament system, of opposite polarity, and when the ratio of the number of turns of ab to the number of turns of de is equal to the ratio of C_{ei} to C_{n1}. The same arrangement and relation applies, of course, to the neutralizing capacity C_{n2} and the output transformer 85 T₂, associated with the second amplifier tube A₂.

Figure 1^d shows the construction of the transformers T₁ and T₂. The primary winding de is mounted so as to have close magnetic coupling to the tapped portion ab of the secondary coil ac, the tap b connecting to the neutralizing condenser C_{n1} or C_{n2}, as shown in Figure 1^e. To make the coupling as close as possible between the auxiliary coil ab and the radio-frequency plate circuit, the leads from d and e and the leads to the plate by-pass condenser C_{p1} or C_{p2}, Figure 1^e, should be made as short as possible. Such closeness of coupling is needed because the radio-frequency current flowing conductively through the plate of the vacuum tube would build up an appreciable voltage in the leakage reactance of the plate circuit, which voltage would not be balanced by a voltage in the auxiliary coil ab. The primary and secondary coils in Figure 1^d are wound in the same direction, with the result that terminal a connecting to the filament system, Figure 1^e, is of opposite polarity to terminal e also connected to the filament system, (or, in other words, the low-potential terminals a and e are of opposite polarity, and the same is therefore true of the high-potential terminals c and d), as required for the purpose of neutralization. The connection of the neutralizing condenser to a tap b, so that ab is a small portion of the secondary winding, allows close coupling to be obtained between ab and de and at the same time requires the primary winding de to extend under only a small portion of the secondary, thus minimizing natural capacity and dielectric loss due to the dielectric field between primary and secondary. The primary winding, as indicated, is placed adjacent to the filament end a of the secondary winding, for the same purpose. In general, there will exist natural capacity between the apparatus connected to the 130

grid of A_1 and apparatus connected to the grid of A_2 . Such natural capacity has a neutralizing tendency and so, in part, supplements C_{n1} . This neutralizing capacity is 5 relatively more effective, for a given value, as the ratio of turns of ac to de is greater than that of ab to de . On account of the difficulty of accurately measuring or calculating very small capacities, particularly 10 natural capacities, the proper neutralizing capacities C_{n1} and C_{n2} , Figure 1^c, are in practice determined by trial. A suggested procedure for neutralizing is as follows: First, with the filament of A_2 cold, and those of 15 A_1 and D lighted, a strong signal is tuned in, as heard on a telephone receiver plugged in the detector plate circuit; C_{n2} is then adjusted until the signal disappears, showing that no coupling exists between the plate 20 circuit and the grid circuit of A_2 . Then with the filaments of D and A_2 lighted and that of A_1 cold, the process is repeated with C_{n1} .

On account of the proximity of the radio-frequency transformers to one another and more especially of the presence of a loop formed by the leads between each secondary and its tuning condenser, the actual coil inclination for zero magnetic coupling may 25 differ slightly, but appreciably, from its theoretical value of substantially 55 degrees. Hence, the proper inclination must also be determined by trial, and may be in accordance with the following procedure: With all 30 coils at the same inclination, C_{n1} and C_{n2} are adjusted for zero coupling as described in the preceding paragraph, with the circuits tuned first for a low frequency and then for a high frequency. In general, the settings 35 found for the two frequencies will be different, showing that the capacity coupling, which varies with the frequency, is being called upon to compensate for some magnetic coupling. The coil inclinations are 40 then varied together, until the settings of C_{n1} and C_{n2} are found to be the same at the two extreme frequencies.

The determination of the proper coil angle need ordinarily be made only once 45 for a given design of receiver, but the adjustments of the neutralizing capacities are made in each individual receiver.

The transformer T_a preferably has a like 50 secondary coil to T_1 and T_2 , but its primary coil usually should have more turns, especially if the antenna to be employed is of 55 small capacity and resistance. With a considerable step-up ratio, the capacity and the resistance of the antenna are equivalent to 60 much smaller capacity and resistance in the secondary circuit.

With the antenna polarity indicated by T_a , Figure 1^c, adjacent turns of primary and secondary are at the same radio-frequency potential, so there is no dielectric field be-

tween primary and secondary as there is in T_1 and T_2 . Hence T_a has less natural capacity than T_1 and T_2 , which tends to compensate for the capacity added by the antenna. The three condensers being alike, 70 the three tuning dials represented in Figure 1^b will thus read nearly alike when all are adjusted to any one frequency. This greatly simplifies the process of tuning the receiver. The result just described, i. e., 75 that all tuning dials will read substantially alike when in proper adjustment for reception, is of course dependent upon the absence of regenerative action, and contrasts with prior receivers employing tuned radio-frequency amplification without the elimination of undesirable coupling between stages; for in such receivers detuning of the amplifier output circuits was ordinarily necessary 80 for the control of regeneration and oscillation, and in any case the tuning adjustment was dependent upon the regeneration present and therefore upon the state of the batteries and of the vacuum tubes.

Figure 2 illustrates a two-tube radio receiver in which the tube A_1 is used both as a radio-frequency and an audio-frequency amplifier. In the receiving apparatus illustrated by this figure, neutralization of capacity coupling between the input and output circuits of tube A_1 is attained through utilization of the natural capacity C_n existing between the apparatus connected to the grid of tube A_1 and the grid of tube D respectively. This natural capacity may readily be made too large by mounting the two variable condensers C_a and C_1 close together. An adjustable grounded metallic shield S may then be introduced between these two condensers and moved until neutralization 95 is attained. Such neutralization could likewise be effected by the capacity between the tuning condensers of several radio-frequency stages. As pointed out in my United States Letters Patent first above-mentioned, neutralization will obtain when the value of the effective grid-plate capacity of tube A_1 divided by the value of capacity represented by C_n is numerically equal to the number of turns of coil L_{s1} divided by the number of turns of the coil L_{p1} , provided the value of coupling between L_{p1} and L_{s1} be sufficient. 100

It is also essential that the relative polarities of the coils L_{p1} and L_{s1} be arranged in accordance with the description given in my United States patents and pending applications previously mentioned, and to that end it is necessary in the present instance that the high-potential terminal of the primary coil L_{p1} be of opposite polarity to the high-potential terminal of the secondary coil L_{s1} . As previously suggested, it is possible to arrange portions of apparatus other than the variable condensers referred to with 105 sufficiently close electrostatic relation to at- 110

tain the degree of neutralization desired: for example, the input and output transformers associated with the tube A_1 and having secondary coils L_s and L_{s1} respectively 5 may be so arranged as to include the required neutralizing capacity between their windings; or both together may be used.

It is to be understood that in the receiver represented by the circuit diagram of Figure 2, the radio-frequency transformers employed to couple the antenna to the first radio-frequency amplifier stage and also the transformers employed to couple successive tubes are to be arranged in such a manner as 10 to eliminate as far as possible all magnetic coupling between the different transformers. Such electromagnetic isolation may be achieved through the use of electromagnetic shielding as described and illustrated in the 15 patent specifications first referred to, or by mounting the transformers with their axes parallel and at an angle of substantially 55° to the common line of centers of the coils, as described in my U. S. Letters Patent No. 1,577,421 previously mentioned.

I claim:

1. In a radio-frequency amplifier including a vacuum tube having an input circuit and an output circuit, said circuits being undesirably coupled by capacity, apparatus including a coil in said input circuit and apparatus including a transformer in said output circuit, the method of reducing the undesirable capacity coupling between said input and output circuits which comprises arranging the high-potential terminal of the primary coil of said transformer to be of opposite polarity to the high-potential terminal of a secondary coil thereof, placing a 20 portion of the apparatus connected to said secondary coil so as to have natural capacity to a portion of the apparatus connected to the coil in said input circuit, interposing an electrostatic shield between said portions of apparatus, and adjusting the position of said shield, whereby said undesirable capacity coupling is at least partially neutralized.
2. A radio-frequency amplifier including a vacuum tube having a filament system, an input circuit and an output circuit, said circuits being undesirably coupled by capacity, apparatus including a coil in said input circuit, and apparatus including a transformer in said output circuit, portions of said apparatus being in electrostatic relation to each other, the high-potential terminal of the

primary coil of said transformer being of opposite polarity to the high-potential terminal of a secondary coil thereof, whereby said undesirable capacity coupling is at least 60 partially neutralized, and an electrostatic shield maintained substantially at the alternating-current potential of said filament system, said shield being adjustably interposed between said portions of apparatus 65 wherewith to effect adjustment of said neutralization.

3. In a tuned radio-frequency amplifier including a vacuum tube having an input circuit and an output circuit, said circuits being undesirably coupled by capacity, a coil and a variable tuning condenser in said input circuit, a transformer in said output circuit, and a variable condenser connected across a secondary coil thereof for tuning 70 the same, the method of reducing the undesirable capacity coupling between said input and output circuits which comprises arranging the high-potential terminal of the primary coil of said transformer to be of opposite 75 polarity to the high-potential terminal of said secondary coil thereof, placing said tuning condensers in electrostatic relation to each other, interposing an electrostatic shield between said condensers, and adjusting the 80 position of said shield whereby to effect at least partial neutralization of said undesirable capacity coupling.

4. A tuned radio-frequency amplifier including a vacuum tube having a filament 85 system, an input circuit and an output circuit, said circuits being undesirably coupled by capacity, a coil and a variable tuning condenser in said input circuit, a transformer in said output circuit, and a variable condenser 90 connected across a secondary coil of said transformer for tuning the same, the high-potential terminal of the primary coil of said transformer being of opposite polarity 95 to the high-potential terminal of said secondary coil thereof, said tuning condensers being in electrostatic relation to each other, whereby at least partial neutralization of 100 said undesirable capacity coupling is obtained, and an electrostatic shield maintained substantially at the alternating-current potential of said filament system, said shield being adjustably interposed between 105 said condensers wherewith to effect adjustment of said neutralization.

In witness whereof, I affix my signature.
LOUIS ALAN HAZELTINE.
